United States Patent Office

JAMES EDWARD THORPE, OF ERIE, PENNSYLVANIA, ASSIGNOR TO HIMSELF AND W. J. F. LIDDELL, OF SAME PLACE.

Letters Patent No. 64,166, dated April 23, 1867.

IMPROVEMENT IN STEAM PUMPS.

The Schedule referred to in these Letters Patent and making part of the same.

TO ALL WHOM IT MAY CONCERN:

Be it known that I, JAMES EDWARD THORPE, of Erie, in the county of Erie, and State of Pennsylvania, have invented a new and improved Steam Pump; and I do hereby declare that the following is a full, clear, and exact description thereof, which will enable others skilled in the art to make and use the same, reference being had to the accompanying drawings, forming part of this specification.

This invention relates to the construction and arrangement of parts of a pumping steam engine, whereby the power of the engine is applied to better advantage than it has hitherto been in this class of engines. And the invention consists in operating directly on the water by pistons or plungers, without the ordinary valves, and in the manner hereinafter described.

Figure 1 represents a side elevation of the pumping engine complete.

Figure 2 is a top or plan view.

Figure 3 is an end view, showing the pumping cylinders and interior of the oscillating-valve chamber.

Figure 4 is a section of fig. 3 through the line *z z*, showing the piston in the supply cylinder and the oscillating valve with the chamber. The pumping cylinder is turned down out of its true position in this figure in order to show the two cylinders in connection with the oscillating valve and chamber to better advantage.

Figure 5 is a top view of the oscillating-valve chamber with the cap off.

Figure 6 is a section of fig. 5, through the line *w w*.

Figure 7 is a side view of the steam-engine valve in the cylinder.

Figure 8 is a transverse section of the same taken in the line *x x*, fig. 7.

Figures 9 and 10 represent different views of the steam-engine valve, showing the recesses therein.

Figure 11 is the plan of a horizontal section taken through the line *y y*, fig. 3, showing the piston in the pumping cylinder.

Similar letters of reference indicate like parts.

A, fig. 1, is the steam cylinder; B is the steam chest; C is the pumping cylinder; D is the supply cylinder; E is the oscillating-valve chamber; F is the valve; G is the air-chamber; H is a fly-wheel; J represents the bed of the engine, which supports the whole apparatus. The steam-engine valve is of peculiar construction. It is shown in figs. 7, 8, 9, 10, A' B' C' D'. It has recesses *a*, which allow it to be surrounded by steam in such a manner that it is balanced by the pressure, and cavities *b*, which hold the steam until the valve passes the ports, when the steam rushes into the cylinder. K is the steam valve-rod. It is moved by an arm, L, which is attached to a sleeve, O, on the piston-rod of the steam and pumping engines. This arm strikes tappets *a a*, which are attached to the valve-rod, and the rod is thus moved back and forth at each revolution or stroke of the engine. The steam enters the valve-chest at *b*, and is exhausted at *c*. The piston-rod of the steam engines and the pumping engine is one and the same thing, with a piston for each cylinder, on each end of it. *m* is a crank-shaft, which is supported across the bed J, as seen in fig. 2. This shaft has a crank near its middle which revolves through the upper plate of the bed. It is operated by the steam engine. The momentum of the fly-wheel H carries it over the dead-centres. It has before been stated that the arm L was attached to the piston-rod *N* by a sleeve, O, fig. 1. This sleeve has on its under side two arms *p p*, between which the wrist-box of the crank plays. On the outer end of the crank-shaft *m* there is a disk or crank-wheel, *r*, which has a wrist-pin in it on which is a box, S. As the shaft *m* revolves, this wrist and box move the piston-rod of the supply cylinder D. This is done through a sliding frame, T, which has a slot in which the box plays the same as the central crank-box does between the arms *p p*. The rod of the supply-cylinder piston *t* is attached to this sliding frame. These movements are all effected by the reciprocating motion of the steam engine which revolves the shaft and fly-wheel, while the latter carries the cranks over their dead-centres, as before stated. The action of the steam engine upon the pumping cylinder is direct, both pistons being upon the same rod. The supply cylinder D has no valves. It has only simple apertures or ports for the discharge of the water from it. The piston merely passes back and forth over an aperture in the middle of the cylinder. This aperture is seen at *u*, fig. 3, and also in fig. 4. This is the supply port of the pump, as seen in fig. 4. The water enters the cylinder D, and passes into the pumping cylinder, and the pistons move in the direction of the arrows as shown in figs. 4 and 11. In the movement of the pistons in these two cylinders it must be understood that

the piston in D is at rest a portion of the time, while the other piston, in C, is moving, and that its stroke is much shorter. The movement of the pumping piston forces the water through D and into the chamber of the valve F. This valve F oscillates back and forth, according to the pressure from the pumping piston, covering the ports *r r* alternately. The water is discharged through the aperture X.

Having thus described my invention, what I claim as new, and desire to secure by Letters Patent, is—

The supply cylinder D, constructed and operating substantially as described; in combination with the pumping engine and the oscillating valve F, and chamber E.

I claim the arrangement, substantially as described, for moving the steam valve and the piston of the supply cylinder.

JAMES EDWARD THORPE.
